UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

AUTOMATIC NAUGHT-STOP FOR ADDING-MACHINES.

1,309,898.

Specification of Letters Patent. Patented July 15, 1919.

Application filed February 18, 1916. Serial No. 79,014.

To all whom it may concern:

Be it known that I, WILLIAM W. LASKER, a citizen of the United States, residing in Brooklyn, in the county of Kings and State of New York, have invented certain new and useful Improvements in Automatic Naught-Stops for Adding-Machines, of which the following is a specification.

This invention relates to card accounting machines in general, and more particularly to automatic naught stops.

The present invention is particularly applicable to a machine such as illustrated in the copending application of James Powers, Serial No. 698,887, filed May 22, 1912.

Among the main objects of the present invention, it is aimed to provide a naught stop that will positively anchor the type-carrying sectors in naught printing position when setting pins have not been extended into their path of movement.

These and other features, capabilities and advantages of the present invention will appear from the subjoined detail description of one specific embodiment thereof, illustrated in the accompanying drawings, in which—

Figure 1 is a side elevation, partly in section, showing the naught stops in sector-anchoring position.

Fig. 2 is a fragmental rear elevation of the same.

Fig. 3 is a fragmental view similar to that shown in Fig. 1.

Fig. 4 is a fragmental view similar to Fig. 3, showing a type-carrying sector released from the naught stop.

Fig. 5 is a fragmental view similar to Fig. 3, showing the position of the naught stop when being retracted.

Fig. 6 is a detail perspective of one of the shutters.

Fig. 7 is a detail perspective of one of the setting pins.

Fig. 8 is a fragmental detail showing the position of a shutter relative to a naught stop when the naught stop is in anchored position.

Fig. 9 is a fragmental detail showing the position of a shutter relative to a naught stop when the naught stop is released from its type-carrying sector.

In the embodiment shown in Fig. 1, there

are provided the type segments 11 pivotally mounted on the shaft 12, on which shaft is also pivotally mounted the cheek plates 13 of the retracting rod 14 and the type-carrying sectors 15, the type segments 11 and type-carrying sectors 15 being resiliently connected to the cheek plates 13 by the springs 16, and the sectors 15 and segments 11 connected to one another by the slot and pin connection 17. For operating the retracting rod 14, the link 18, pivotally connecting the cheek plates 13 with the crank sector 19, is secured to the actuating shaft 20. There is also provided a shutter-box 21 provided with the shutters 22, which have inclined upper edges 23 that are resiliently maintained in the path of movement of the setting pins 24 of the shutter-box 21 by the springs 25 (Fig. 2). The shutters 22, in the present instance, as distinguished from those illustrated in the co-pending application of James Powers, Serial No. 802,363, filed Nov. 22, 1913, have, instead of the upwardly extending naught stop, an upwardly extending rear plate portion 26 which, when its shutter is anchored in the path of movement of the pins 24, will serve as the active supporting portion of the naught stop forming the present improvement.

The naught stop forming the present improvement comprises, essentially, pins 27 on the segments 11 to be engaged by the upwardly extending hook arms 28 of the levers 29 pivotally connected to the rod 30 at their rearwardly extending portions 31, such rearwardly extending portions being spaced from one another by the fingers 32 of the spacing bar 33 which is secured to the lower side of the transversely extending block 34 fastened to the rear end of the main frame A, the rod 30 being supported by such fingers 32. The levers 29 are also provided with downwardly extending arms 35 which are adapted to rest on the plate portions 26 of the shutters 22 when the naught stops are disposed in segment-anchoring position.

For further spacing the levers 29 from one another and guiding them in their operation, there are provided the spacing rods 36 which extend from the upwardly extending plate portion 37 secured to the front end of the shutter-box 21 to the downwardly extending plate portion 38 secured to the main

frame A, such rods being of comparatively small diameter and extending between the segments 11 and the levers 29.

From the foregoing it will be seen that, 5 when the segments 11 have been retracted by the retracting rod 14, and the levers 29 are positioned on the plate portions 26, the hook arms 28 will engage the pins 27 and anchor such segments 11 in naught position, 10 and that, whenever a pin 24 is set thereby rocking a shutter 22, it will remove the support for a lever 29 thereby permitting such lever to descend and therewith withdraw its hook arm 28 out of engagement with the 15 pin 27. Thereupon the segments 11 are free to move forwardly and be stopped by the pins 24.

For retracting the levers 29, the lever-retracting rod 39 is provided, which is secured to the free arms of the levers 40 pivotally connected to the downwardly extending portions of the bearing brackets 41 secured to the block 34. Pivotally connected to the upwardly extending portions of the 25 bearing brackets 41 are the levers 42 which extend forwardly, and at their free ends support the cheek plate-engaging rod 43. For moving the rods 43 and 39 in parallelism, the levers 42 and 40 are pivotally connected to one another by the links 44, such links 44, in the present instance, being bent to circumvent the block 34. For resiliently maintaining the rod 43 in its downward position against the cheek plates 13, the 35 springs 45 are provided, connecting the levers 42 with the block 34. For limiting the downward movement of the levers 42, there is provided a limiting rod 46 which is secured to the frame A.

40 The operation of the retracting arrangement is substantially as follows:—When printing has taken place, and the segments 11 are to be returned, the cheek plates 13 are retracted by the link 18. As such cheek plates 13 approach their rearward movement, they will engage the rod 43 and thereby rock the levers 42 and 40 and the lever-retracting rod 39, until the lever-retracting rod 39 engages and raises the levers 29 above 45 the plate portions 26, whereupon the pins 24, having previously been released, the shutters 22 will immediately be returned to normal lever-supporting position, and the lower arms 31 of the levers 29 will therewith 50 engage the upper surfaces of the plate portions 26, while their hook arms 28 will engage the pins 27.

It is obvious that various changes and modifications may be made in the details of 60 construction without departing from the general spirit or scope of this invention.

I claim:

1. In combination with a tabulator printer having type segments, means for positively 65 maintaining said segments in naught print-

ing position, means for supporting said naught stopping means in naught printing position, means for determining the position of said segments for printing position, means for operatively connecting said determining means with said supporting means whereby to rock said supporting means out of supporting position when one of said determining means is positioned thereby permitting the withdrawal of said 70 naught stopping means and permitting the free movement of said segments, retracting means for said type segments, means for restoring said naught stopping means, and means for operatively connecting said segment-retracting means with the restoring means of said naught stopping means so that the withdrawal of said segment-retracting means will actuate said restoring means.

2. In combination with a tabulator printer 85 having type segments, means for positively maintaining said segments in naught printing position, shutters for supporting said naught stopping means in segment-anchor- 90 ing position, means for determining the position of said segments for printing position, and means for operatively connecting said determining means with said shutters whereby to rock such shutters out of supporting position when one of said determining means 95 is positioned, thereby permitting the withdrawal of said naught stopping means and permitting the free movement of said segments.

3. In combination with a tabulator printer 100 having type sectors, means for positively maintaining said segments in naught printing position, shutters for supporting said naught stopping means in segment-anchor- 105 ing position, means for determining the position of said segments for printing position, means for operatively connecting said determining means with said shutters whereby to rock such shutters out of supporting position when one of said determining means is 110 positioned, thereby permitting the withdrawal of said naught stopping means and permitting the free movement of said segments, and resilient means for maintaining said shutters in the path of movement of 115 said determining means, the actuation of said determining means rocking said shutters out of the path of movement of said determining means and thereby also rocking said shutters out of supporting position. 120

4. In combination with a tabulator printer having type segments, pins on said segments, levers pivotally mounted, hook arms on said levers for engaging said pins, to anchor said segments in naught printing 125 position, means for supporting said levers in segment-anchor- position, means for determining the position of said segments for printing position, and means for operatively connecting said determining means with 130

5 said supporting means to rock said supporting means out of supporting position when one of said determining means is positioned thereby permitting the withdrawal of said 5 lever to permit the free movement of said segments.

5. In combination with a tabulator printer having type segments, pins on said segments, levers pivotally mounted, hook arms on said 10 levers for engaging said pins to anchor said segments in naught printing position, means for supporting said levers in segment-anchoring position, means for determining the position of said segments for printing 15 position, means for operatively connecting said determining means with said supporting means to rock said supporting means out of supporting position when one of said determining means is positioned thereby permitting the withdrawal of said 20 levers to permit the free movement of said segments, and means for restoring said levers in segment-anchoring position with the withdrawal of said segments.

25 6. In combination with a tabulator printer having type segments, pins on said segments, levers pivotally mounted, hook arms on said levers for engaging said pins to anchor said segments in naught printing 30 position, means for supporting said levers in segment-anchoring position, means for determining the position of said segments for printing position, means for operatively connecting said determining means with said 35 supporting means to rock said supporting means out of supporting position when one of said determining means is positioned thereby permitting the withdrawal of said levers to permit the free movement of said 40 segments, retracting means for said type segments, means for restoring said levers, and means for operatively connecting said segment-retracting means with the restoring means of said levers.

45 7. In combination with a tabulator printer having type segments, pins on said segments, levers pivotally mounted, hook arms on said levers for engaging said pins to anchor said segments in naught printing 50 position, means for supporting said levers in segment-anchoring position, means for determining the position of said segments for printing position, means for operatively connecting said determining means with said 55 supporting means to rock said supporting means out of supporting position when one of said determining means is positioned thereby permitting the withdrawal of said levers to permit the free movement of said 60 segments, means for restoring said levers in segment-anchoring position with the withdrawal of said segments, retracting means for said type segments, an upper rod disposed to be engaged by said retracting 65 means, a lower rod disposed to engage and

raise said levers into segment-anchoring position, and means for connecting said rods with one another so that the actuation of said retracting means will actuate said lower rod to restore said levers. 70

8. In combination with a tabulator printer having type segments, pins on said segments, levers pivotally mounted, hook arms on said levers for engaging said pins to anchor said segments in naught printing 75 position, means for supporting said levers in segment-anchoring position, means for determining the position of said segments for printing position, means for operatively connecting said determining means with said supporting means to rock said supporting means out of supporting position when one of said determining means is positioned thereby permitting the withdrawal of said levers to permit the free movement 80 of said segments, means for restoring said levers in segment-anchoring position with the withdrawal of said segments, retracting means for said type segments, an upper rod disposed to be engaged by said retracting 85 means, a lower rod disposed to engage and raise said levers into segment-anchoring position, and parallelly moving levers connecting said rods to one another so that the actuation of said retracting means will actuate said lower rod to restore said levers. 90

9. In combination with a tabulator printer having type segments, pins on said segments, levers pivotally mounted, hook arms on said levers for engaging said pins to anchor said segments in naught printing 100 position, means for supporting said levers in segment-anchoring position, means for determining the position of said segments for printing position, means for operatively connecting said determining means with said supporting means to rock said supporting means out of supporting position when one of said determining means is positioned thereby permitting the withdrawal of said 105 levers to permit the free movement of said segments, means for restoring said levers in segment-anchoring position with the withdrawal of said segments, and means for guiding said levers and spacing them from one another. 110

10. In combination with a tabulator printer having type segments, pins on said segments, levers pivotally mounted, hook arms on said levers for engaging said pins to anchor said segments in naught printing 120 position, means for supporting said levers in segment-anchoring position, means for determining the position of said segments for printing position, means for operatively 125 connecting said determining means with said supporting means to rock said supporting means out of supporting position when one of said determining means is positioned thereby permitting the withdrawal of said 130

levers to permit the free movement of said segments, means for restoring said levers in segment-anchoring position with the withdrawal of said segments, retracting means 5 for said type segments, an upper rod disposed to be engaged by said retracting means, a lower rod disposed to engage and raise said levers into segment-anchoring position, parallelly moving levers connecting 10 said rods to one another so that the actuation of said retracting means will actuate said lower rod to restore said levers, and means for resiliently maintaining said parallelly moving levers in depressed position 15 where the upper rod engages the retracting means.

11. In combination with a tabulator printer having type segments, pins on said segments, levers pivotally mounted, hook 20 arms on said levers for engaging said pins to anchor said segments in naught printing position, means for supporting said levers in segment-anchoring position, means for determining the position of said segments 25 for printing position, means for operatively connecting said determining means with said supporting means to rock said supporting means out of supporting position when one of said determining means is positioned 30 thereby permitting the withdrawal of said levers to permit the free movement of said segments, means for restoring said levers in segment-anchoring position with the withdrawal of said segments, retracting means 35 for said type segments, an upper rod disposed to be engaged by said retracting means, a lower rod disposed to engage and raise said levers into segment-anchoring position, parallelly moving levers connecting 40 said rods to one another so that the actuation of said retracting means will actuate said lower rod to restore said levers, means for resiliently maintaining said parallelly moving levers in depressed position where the 45 upper rod engages the retracting means, and means for limiting the lower movement of said parallelly moving levers.

12. In a combination with a tabulator printer having type segments, pins on said 50 segments, levers pivotally mounted for engaging said pins to anchor said segments in naught printing position, means for supporting said levers in segment-anchoring position, means for determining the position 55 of said segments for printing position, means for operatively connecting said determining means with said supporting means to rock said supporting means out of supporting position when one of said determining means is positioned, thereby permitting the withdrawal of said levers to permit the free movement of said segments, means for restoring said levers in segment-anchoring position with the withdrawal of said 60 segments, retracting means for said type

segments, a member disposed to be engaged by said retracting means, a member disposed to engage and raise said levers into segment-anchoring position, and means for connecting said members with one another so that 70 the actuation of said retracting means will actuate one of said members to restore said levers.

13. In combination with a tabulator printer having type segments, pins on said 75 segments, levers pivotally mounted for engaging said pins to anchor said segments in naught printing position, means for supporting said levers in segment-anchoring position, means for determining the position 80 of said segments for printing position, means for operatively connecting said determining means with said supporting means to rock said supporting means out of supporting position when one of said determining 85 means is positioned thereby permitting the withdrawal of said levers to permit the free movement of said segments, means for restoring said levers in segment-anchoring position with the withdrawal of said segments, retracting means for said type segments, a member disposed to be engaged by said retracting means, a member disposed to engage and raise said levers into segment-anchoring position, and parallelly 90 moving elements connecting said members to one another so that the actuation of said retracting means will actuate one of said members to restore said levers.

14. In combination with a tabulator printer having type segments, pins on said 95 segments, levers pivotally mounted for engaging said pins to anchor said segments in naught printing position, means for supporting said levers in segment-anchoring 100 position, means for determining the position of said segments for printing position, means for operatively connecting said determining means with said supporting means to move said supporting means out of supporting position when one of said determining 105 means is positioned thereby permitting the withdrawal of said levers to permit the free movement of said segments, means for restoring said levers in segment-anchoring 110 position with the withdrawal of said segments, and means for guiding said levers and spacing them from one another.

15. In combination with a tabulator printer having type segments, pins on said 115 segments, levers pivotally mounted for engaging said pins to anchor said segments in naught printing position, means for supporting said levers in segment-anchoring 120 position, means for determining the position 125 of said segments for printing position, means for operatively connecting said determining means with said supporting means to move said supporting means out of supporting position when one of said determin- 130

ing means is positioned thereby permitting the withdrawal of said levers to permit the free movement of said segments, means for restoring said levers in segment-anchoring position with the withdrawal of said segments, retracting means for said type segments, an upper member disposed to be engaged by said retracting means, a lower member disposed to engage and raise said levers into segment-anchoring position, parallelly moving elements connecting said members to one another so that the actua-

tion of said retracting means will actuate said lower member to restore said levers, means for resiliently maintaining said parallelly moving elements in depressed position while the upper member engages the type segment retracting means, and means for limiting the lower movement of said parallelly moving levers.
